UNITED STATES PATENT OFFICE.

WILLIAM A. ANSLEY, OF PORT WASHINGTON, NEW YORK, ASSIGNOR TO SWANSDOWN KNITTING COMPANY, OF HUDSON, NEW YORK, A CORPORATION OF NEW YORK.

DESIGN FOR A BUTTON OR SIMILAR ARTICLE.

Application filed November 30, 1921. Serial No. 519,013. Term of patent 14 years.

To all whom it may concern:

Be it known that I, WILLIAM A. ANSLEY, a citizen of the United States, residing at Port Washington, county of Nassau, and State of New York, have invented a new, original, and ornamental Design for Buttons or Similar Articles, of which the following is a specification, reference being had to the accompanying drawing, forming a part thereof.

The figure is a plan view of a button or similar article showing my new design.

I claim:

The ornamental design for a button or similar article substantially as shown.

WILLIAM A. ANSLEY.
